Inventor:
W. R. McComas.

UNITED STATES PATENT OFFICE.

WILLIAM R. MCCOMAS, OF OAKLEY, OHIO, ASSIGNOR TO THE CRANE & BREED MANUFACTURING COMPANY, OF OHIO.

DESIGN FOR AN EMBLEMATIC COFFIN-HANDLE.

SPECIFICATION forming part of Design No. 13,321, dated September 26, 1882.

Application filed August 25, 1882. Term of patent 3½ years.

To all whom it may concern:

Be it known that I, WILLIAM R. MCCOMAS, a citizen of the United States, residing at Oakley, county of Hamilton, and State of Ohio, have invented and produced a new and original Design as an Emblematic Ornament for the Handle-Supporting Bracket of a Coffin or Casket, of which the following is a specification, reference being had to the accompanying drawing, forming part thereof.

The figure is a front elevation of my newly-designed bracket-handle.

My invention is an emblematic ornament for the bracket supporting the handle of a coffin or burial-case; and it consists of an ear or lug with a cherub in a bank of clouds surrounding the ear, the cherub being supported upon the semicircular shell of the lug, with its arms raised and its hands in the act of being folded,

the fingers touching. The cherub has perpendicular wings extending up by its head, with their tips supporting, above the head, a radiant star, as shown, the whole being adapted to be secured by screws to the side of the coffin.

Having thus fully described my invention, what I claim, and desire to secure by Letters Patent, is—

An ornamental lug or bracket for coffin-handles, consisting of a cherub in a bank of clouds, with hands folded and with perpendicular wings supporting between their tips a radiant star just above the head of the cherub, substantially as described.

WM. R. MCCOMAS.
